UNITED STATES PATENT OFFICE.

HENRY YOUMANS, OF CANNON FALLS, MINNESOTA.

CLOTHES-POUNDER.

SPECIFICATION forming part of Letters Patent No. 425,360, dated April 8, 1890.

Application filed November 29, 1889. Serial No. 331,936. (No model.)

To all whom it may concern:

Be it known that I, HENRY YOUMANS, of Cannon Falls, in the county of Goodhue and State of Minnesota, have invented certain new 5 and useful Improvements in Clothes Pounders or Washers; and I do hereby declare the following to be a full, clear, and exact description of the invention, such as will enable others skilled in the art to which it pertains 10 to make and use it, reference being had to the accompanying drawing, which forms part of this specification.

My invention relates to an improvement in clothes pounders or washers; and it consists 15 in the combination and arrangement of parts, to be more fully described hereinafter, and particularly pointed out in the claim.

The object of my invention is to place upon 20 a clothes-pounder a vertically-movable cone which catches the water or splash caused by the other cones and prevents it from splashing upon the floor, and to extend upward the upper end of one of the rigid cones sufficiently far to provide a smooth and hard bearing- 25 surface for the movable cone to slide upon.

The accompanying drawing is a vertical section of a washer which embodies my invention, the splasher being shown in one position in solid lines and in another in dotted lines.

30 A represents the handle, and B the center cone, which is considerably shorter than the outer one C. These two cones operate in the usual well-known manner in clothes-pounders of this class. Placed upon the handle and dropping down over and around the two cones 35 B C is a third cone D, which, instead of being rigidly secured to the handle like the other

two cones, is made automatically and vertically movable, so that as the pounder is moved up and down this outer cone D catches the 40 water which would be splashed out upon the floor by the other two cones. The cone C is provided with the elongated end G, which extends up and around the handle A, as shown, and which forms a smooth bearing-surface for 45 the moving cone D, which is placed around it. As the handle is forced downward the two cones B C in striking the water cause a considerable splash and the outer cone D rises upon the handle just sufficiently to catch this 50 splash without making any additional splash from its own movement. The consequence is the machine can be operated without causing much if any splash.

Having thus described my invention, I 55 claim—

The combination, with a clothes-pounder consisting of a handle, and rigid imperforate cones placed upon the lower end thereof, of a larger imperforate movable cone the lower edge of 60 which extends down and surrounds the lower end of the rigid cone, and so loosely placed upon the handle that it rises and falls from the momentum of the pounder, whereby it is moved downward and catches the splash of 65 the rigid cones, substantially as shown and described.

In testimony whereof I affix my signature in presence of two witnesses.

HENRY YOUMANS.
